**MEANS TO CAUSE VIBRATION OF RING RAIL
OF SPINNING FRAME**
James W. Stuart, P.O. Box 600, Greer, S.C.
Filed Feb. 7, 1964, Ser. No. 343,249
6 Claims. (Cl. 57—137)

This invention relates to spinning frames and more particularly to spinning frames of the movable ring rail type and to means for causing the ring rail to vibrate during the operation of the spinning frame.

It is a known fact that limitations on the speed of operation of a spinning frame are due in part to the friction between the ring travelers and the rings mounted on the ring rail. If the speed is excessive, the friction on the traveler increases to a point where the traveler may actually burn or disintegrate. Any means to effectively increase the speed of operation of the traveler and the spinning machine as a whole will necessarily result in a higher production of yarn with economy, which is the basic object of the invention.

A further advantage of the invention and a further economy incident to the invention resides in increasing the life of the traveler by the elimination of the friction wear thereon or greatly reducing this friction.

According to the invention, simplified means is employed to produce relatively high speed vibration of the entire ring rail, both vertically and horizontally during the operation of the frame. The ring rail is resiliently mounted on its lifting rods to enhance this vibration. In effect, the ring travelers are caused to quiver, vibrate or dance as they pass around the rings, thus reducing to a minimum the friction between the rings and travelers without adversely effecting the operation of spinning the yarn and building bobbins in an otherwise normal manner.

Other objects and advantages of the invention will be apparent during the course of the following detailed description.

In the accompanying drawings forming a part of this application and in which like numerals are employed to designate like parts throughout the same,

FIGURE 1 is a fragmentary partly diagrammatic front elevational view of a spinning frame having the invention applied thereto.

FIGURE 2 is an enlarged central vertical section through the ring rail vibrating means and showing the same attached to one end portion of the ring rail, and

FIGURE 3 is an enlarged fragmentary vertical section through the ring rail and one lifter rod thereof and showing one of the resilient ring rail cushioning elements to facilitate vibration.

In the drawings, wherein there is shown one simplified embodiment of the invention, attention is directed to FIGURE 1 illustrating pertinent portions of a conventional spinning frame of the movable ring rail type. In this figure, the numeral 10 designates the usual fixed spindle rail, upon which the several vertical spindles 11 are journaled for rotation. Bobbins 12 are mounted upon the spindles 11 to turn therewith so that yarn can be guided thereto by the vertically movable ring rail 13 carrying the usual rings 14 and traveler elements 15.

The ring rail 13 is supported at plural points along its length by lifter rods 16 which are biased upwardly by the usual counterweighted lifter mechanisms or arms 17, all conventional in the art. The ring rail 13 is drawn downwardly during its traversing of the bobbins by a flexible element 18 attached at one end to a quadrant 19 on the lifter mechanism and also trained over a pulley 20 near one end of the spindle rail, where the element 18 is directed to the usual builder motion, not shown. This

2

construction and its mode of operation is well known in the art and need not be further dealt with herein.

The invention proper, as stated, is a means to impart vibration to the ring rail 13 and travelers 15 during the normal operation of the spinning frame. Such means in the embodiment illustrated comprises a relatively small housing 21, rigidly secured at 22 to the ring rail 13 near one end thereof. The housing 21 has an internal annular passage or race 23 disposed in a vertical plane with a generally tangential compressed air inlet port 24 leading into the passage 23 near the top thereof and a smaller exhaust port 25 leading from the passage 23 near the bottom thereof. The housing 21 is adapted to have a compressed air hose 26 or the like connected with the inlet port 24, as shown in FIGURE 1, and the hose 26 leads to a suitable source of compressed air, not shown. A steel ball 27 or the like is contained loosely within the annular passage 23 and is adapted under the influence of compressed air admitted through the port 24 to travel rapidly and continuously through the annular passage 23. This movement of the ball 27 imparts effectively to the entire ring rail 13 relatively high speed vibration or oscillation in the vertical as well as the horizontal direction during the operation of the spinning frame. As the ball 27 travels through the annular passage 23 at high speed, it generates powerful vibrations in all directions continuously.

In conjunction with the ring rail vibrating means above-described, the ring rail 13 is resiliently cushioned at all of its points of attachment to the lifter rod 16 by means of rubber-like cushioning pads 28 interposed between the tops of the rods 16 and the lower surface of the ring rail and secured thereto at 29, as shown in FIGURE 3.

When the spinning frame is in operation for building the bobbins with yarn, compressed air is continuously supplied at 24 to the annular passage 23, and the ball element 27 continuously travels within the passage 23 and imparts vibration vertically and horizontally to the entire ring rail which floats to a degree on the pads 28. This vibration of the ring rail is transmitted to the travelers 15 which in turn quiver or vibrate as they move rapidly around the rings 14. The vibration of the travelers reduces their frictional contact with the rings to a minimum and, in effect, causes the travelers to float to a great extent out of contact with the rings during their movement or to have only occasional or limited direct engagement with the rings. This materially reduces the friction between the travelers and rings and makes possible a much higher speed of operation of the travelers and bobbins and the entire spinning frame, resulting in a higher production of yarn.

The invention is very simple, economical and does not require any material altering of the conventional ring rail or spinning frame structure and no change in the usual operation of the frame. The invention may be applied with facility to existing spinning frames or to new frames at the time of manufacturing thereof. It is thought that the advantages of the invention will be readily apparent to those skilled in the art without the necessity for any further description.

It is to be understood that the form of the invention herewith shown and described is to be taken as a preferred example of the same, and that various changes in the shape, size and arrangement of parts may be resorted to, without departing from the spirit of the invention or scope of the subjoined claims.

Having thus described my invention, I claim:

1. In a spinning frame, a movable ring rail to traverse bobbins during the building of the bobbins with yarn, and means bodily mounted on the ring rail to impart vibration thereto bodily during the operation of the spinning frame.

2. In a spinning frame, a movable ring rail, a plurality of rings on said ring rail, travelers on said rings to move around the same, and means bodily mounted on the ring rail to vibrate the ring rail during operation of the spinning frame, such vibration being transmitted to the rings and travelers, whereby the frictional engagement between the rings and travelers is greatly reduced.

3. In a spinning frame, a movable ring rail, lifter rods carrying said ring rail, resilient cushioning means interposed between the ring rail and lifter rods at the points of attachment of the rail to the rods, and means on the ring rail operable during the movement of the ring rail to impart vibration to the ring rail in a horizontal and also in a vertical direction.

4. In a spinning frame, a movable ring rail, resilient means carrying the ring rail and cushioning the same, rings and travelers mounted upon the ring rail, and a vibration unit mounted upon the ring rail to impart vibration thereto and to said travelers during the normal operation of the spinning frame.

5. The invention as defined by claim 4, and wherein said resilient means includes rubber-like pads interposed

between the ring rail and ring rail lifter rods and secured thereto.

6. The invention as defined by claim 4, and wherein said vibration unit comprises a housing secured to one end portion of the ring rail and having an annular chamber in a substantially vertical plane and fluid inlet and outlet ports leading to and from said chamber, and a vibration element arranged loosely within said chamber and adapted to be moved through the chamber at high speed under the influence of fluid passing to the chamber from said inlet port.
